SYRINGE PUMP FOR MEDICAL AND LABORATORY USE

David Rosenberg, Glen Cove, N.Y., assignor to Pall Corporation, Glen Cove, N.Y., a corporation of New York

Filed June 4, 1969, Ser. No. 17,942

Term of patent 14 years

Int. Cl. D24—02

U.S. Cl. D83—1

FIG. 2

FIG. 1

FIG. 3

FIG. 4

FIG. 1 is a front view of a surgical syringe pump, showing my new design;

FIG. 2 is a top plan view thereof;

FIG. 3 is an end elevation thereof; and

FIG. 4 is a bottom perspective view thereof.

The broken lines representing the syringe is shown for illustrative purposes only and does not form part of the claim.

I claim:

The ornamental design for a syringe pump for medical and laboratory use, substantially as shown and described.
